United States Patent Office.

LEVI O. ALLEN, OF GARDINER, MAINE.

Letters Patent No. 84,930, dated December 15, 1868.

IMPROVEMENT IN STOVE-PIPE DAMPERS.

The Schedule referred to in these Letters Patent and making part of the same.

To all whom it may concern:

Be it known that I, LEVI O. ALLEN, of Gardiner, county of Kennebec, State of Maine, have invented a new and useful Improved Stove-Damper; and I do hereby declare that the following is a full and clear description thereof, reference being had to the accompanying drawings, and to the letters of reference marked thereon.

In the drawings—

Figure 1 represents a side sectional view of a stove-pipe with my damper;

Figure 2, a cross-section of pipe, showing the bottom view of the damper; and

Figure 3, another sectional view, vertically cut through the pipe.

This invention consists of a damper which shall reflect back the heat when shut, and still allow the escape of the smoke in a sufficiently rapid manner to keep up the fire.

In construction, I form my damper of two semi-ovate plates, hinged together at the straight sides. These plates, A and A', are constructed of such a size and shape, in reference to the pipe in which they are to be placed, that when spread out to the full limit allowed by the sides of the pipe, they being centrally hinged in the same, they will form an angle of ninety degrees to each other, and forty-five from the horizontal line drawn across its axis. This, however, is not imperative, but only gives the greatest per cent. of reflected heat, which, generally moving upwards in the central part of the flue, is thrown back, and the smoke allowed to pass by the edges of the plates A and A', scallops *a a*, &c., being cut around their edges in order to prevent a too close joint.

The manner of operating these plates is as follows:

The plates A and A' are hinged upon a shaft, B, which is arranged in the stove-pipe so that it can be moved longitudinally through it.

Each plate has one socket, c, which meet in the middle.

In the bottom side of these sockets are cut slots D

and D', inclining spirally in opposite directions, one slot to each socket.

On the shaft are placed pintles E and E', which, when the shaft is pushed in through the pipe, throw up the plates A and A' to a vertical position, as shown in red lines in fig. 2.

A key, F, attached to the shaft, or formed upon it, and fitting into a corresponding key-seat cut into the under side of the shaft-hole G, in the pipe, prevents the shaft from turning, as it forces the plates up; and a washer, H, on the other end of the shaft, prevents it from being pulled through the pipe.

This washer is made with a hole in the lower part large enough to be slipped over the shaft, and a smaller socket in the upper part, into which the neck of the shaft-end is slipped, thus preventing the washer from coming off, unless lifted up, until the lower hole is on a line with the shaft.

The advantages of this device are, that I obtain a simple and cheap damper, easily manufactured, and one that reflects back the greatest per cent. of heat from the flue.

Having described my invention,

What I claim as new, and desire to secure by Letters Patent, is—

1. The combination and arrangement of the two semi-ovate plates A and A', hinged together upon and operated by a common shaft, B, put through the pipe or flue horizontally, substantially as herein shown and described.

2. The arrangement of the slots D and D', in combination with the pintles E and E', upon the shaft B, substantially as shown.

3. In combination with the shaft B, the key F and washer H, arranged and constructed as described and shown.

LEVI O. ALLEN.
